UNITED STATES PATENT OFFICE.

JOSEPH NEWTON MACDONALD, OF ARLINGTON, MASSACHUSETTS.

BUILDING CONSTRUCTION.

Application filed October 6, 1921. Serial No. 505,986.

To all whom it may concern:

Be it known that I, JOSEPH NEWTON Mac-
DONALD, a citizen of the United States, and
a resident of Arlington, in the county of
Middlesex and State of Massachusetts, have
invented a new and Improved Building
Construction, of which the following is a
full, clear, and exact description.

This invention relates to improvements
10 in building constructions, an object of the
invention being to provide an improved
hollow wall construction, wherein the cost
of construction is reduced to a minimum,
and a building may be constructed in a
15 minimum amount of time.

A still further object is to provide cer-
tain improved fastening means for holding
the blocks in a wall together, which will do
away in a great measure the use of mortar.

20 Still another object is to provide a hol-
low wall construction for buildings which
will be damp-proof, and which will be sim-
ple, practical and durable.

With these and other objects in view, the
25 invention consists in certain novel features
of construction and combinations and ar-
rangements of parts as will be more fully
hereinafter described and pointed out in the
claims.

30 In the accompanying drawings:

Figure 1 is a fragmentary perspective
view looking at the outside of a hollow
wall;

Figure 2 is a similar view taken from
35 the inside of a wall;

Figure 3 is an enlarged fragmentary view
in transverse section on the line 3-3 of
Figure 1;

Figure 4 is a similar view on the line 4-4
40 of Figure 2;

Figure 5 is a sectional view;

Figure 6 is a perspective view of one of
the connecting irons;

Figure 7 is a perspective view of one of
45 the reinforcing elements; and

Figure 8 is a perspective view of one of
my improved fastening members.

Referring in detail to the drawings, it
will be seen that I provide a hollow wall
50 building construction which comprises an
inner wall 1 and an outer wall 2 spaced
apart. Each wall is formed of relatively
thin rectangular slabs or panels 3, arranged
in superimposed rows. As is customary in
55 the art, the intermediate portions of one
row of blocks or panels cover the corners of

the blocks upon which they are superim-
posed. The panels in the outside wall are
preferably provided upon their inner face
with a coat of waterproof material, desig-
60 nated by the reference numeral 4. The
blocks may either be treated to obtain this
waterproof finish, or may be covered with
any suitable material for the purpose.

The blocks of the outside wall are secured
65 together by mortar in the customary manner
and the blocks of the inside wall are re-
tained in position by an improved fastening
means to be more fully described herein-
after. Adjacent the end of each block, there
70 are provided in the upper edges of the blocks
recesses, such as 5. The walls of these re-
cesses are reinforced by any suitable devices,
designated by the reference numeral 6, em-
bedded in the blocks. Obviously the rein-
75 forcing members 6 might take an infinite
variety of shapes and any reinforcing mem-
ber which includes a pair of looped elements
7 cooperating to form a strengthening band
in the walls of the recesses might be used.
80

I have used the numeral 8 to designate
connecting irons of substantially U-shape
and including at their ends arms 9 which
are adapted to fit into the recesses 5 in the
blocks of the inner and outer walls and
85 firmly connect the walls. Short transverse
depressions 10 in the upper edges of the
blocks communicate with the recesses 5 so
that the intermediate portions of the con-
necting irons 8 are located below the planes
90 of the upper edges of the blocks and do not
interfere with the superimposition of the
blocks one upon the other.

It has been previously noted that the
blocks of the inner wall are secured together
95 by fastening members rather than by mortar,
these fastening members not only reducing
the cost of construction, but also expediting
the assembling of the blocks. The form of
the fastening members, designated in their
100 entirety by the reference numeral 11, is
shown clearly in Figure 8, where it will be
seen that the fasteners comprise lengths of
wire, the intermediate portions 12 of which,
are bent into substantially U-shape. The
105 ends of the wire leading from the extremi-
ties of the arms of the U are then curled into
substantially circular shape, as indicated at
13, the circular members being located in a
transverse plane to the plane of the inter-
110 mediate portion of the U and forming in
effect wheels, each having one radial spoke

14 connected by an axle which forms the intermediate portion of the wire. The fasteners are applied at the corners of the blocks in the inside wall, the intermediate 5 portion 12 thereof resting on the blocks and supporting the fasteners, and the circular members being located upon opposite sides of the blocks in the wall and tending to securely hold the same against lateral 10 placement.

It has heretofore been noted that the shape of the reinforcing members 6 might be considerably changed without affecting their usefulness. The exact shape of the 15 fastener members 11 might also be modified and various other slight changes and alterations might be made in the general form and arrangement of the parts described without departing from the invention and 20 hence I do not wish to limit myself to the precise details set forth, but shall consider myself at liberty to make such slight changes and alterations as fairly fall within the spirit and scope of the appended 25 claims.

In constructing partition walls, the use of mortar is done away with entirely and the hollow wall comprises an inner and outer shell both secured together by the fasteners 30 illustrated in Figure 8 and connected by the irons hereinbefore described.

I claim:

1. In a hollow wall construction, a pair of spaced walls, each comprising superimposed tiers of relatively thin slabs, said slabs having vertical recesses in their top faces and transverse grooves leading from the recesses out through the inner faces of the slabs, reinforcing members having openings at about the middle of their length and 35 embedded in the slabs adjacent their top

faces and extending longitudinally thereof with their openings registering with the recesses of said slabs, and U-shaped irons connecting the walls, the arms of the irons being located in the openings of the reinforcing members and the recesses of the slabs and the body portion adjacent the arms lying in the grooves. 45

2. In a hollow wall construction, a pair 50 of spaced walls, each comprising tiers of relatively thin slabs, said slabs having vertical recesses in their top faces, reinforcing wire members having looped ends and coils at the center of their length, said members 55 being embedded in the slabs and extending longitudinally thereof with their coils registering with the recesses of the slabs, and U-shaped irons connecting walls, the arms of the irons being located in the coils of 60 the reinforcing members and the recesses of the slabs. 65

3. In a wall construction, a series of superimposed slabs, fastener elements retaining said slabs in vertical alinement, each 65 element comprising a U-shaped member having the extremities of its arms bent into ring-shape.

4. In a hollow wall construction, a pair 70 of spaced walls, each comprising a plurality of superimposed slabs having recesses in their top faces, reinforcing members having openings and embedded in the slabs with their openings registering with the recesses of the slabs, U-shaped bars extending between the walls and having their arms engaging the recesses of the slabs, and fastening members securing the slabs of each wall together and in vertical alinement, said 75 members having enlarged ends to engage 80 the inner and outer faces of adjacent slabs. 85

JOSEPH NEWTON MacDONALD.
